HOWARD M. BARBER, OF PAWCATUCK, CONNECTICUT, ASSIGNOR TO C. B. COTTRILL & SONS COMPANY, OF WESTERLY, RHODE ISLAND, A CORPORATION OF DELAWARE.

COLLECTING, FOLDING, AND DELIVERING MECHANISM FOR PRINTING PRESSES.

Application filed May 7, 1927. Serial No. 189,551.

In rotary printing presses it is often necessary to make the plate cylinder large enough to carry six plates around its circumference in order to obtain a rigid impression; four plates around making the cylinder too small and eight plates around making it too large. Heretofore in signature collecting, folding and delivery mechanisms designed for use in connection with printing presses having plate cylinders with six plates around their peripheries it was only possible to fold and deliver the product in 12, 24 and 48 page signatures. The object of my invention is to provide improvements in the signature collecting, folding and delivery mechanism for this type of press whereby products of 8 page signatures and multiples of 8s can be collected, folded and delivered; this being accomplished by providing a double folder, each collecting, folding and delivery mechanism comprising a four-way collecting cylinder and coacting folding cylinders three-fourths the diameter of the collecting cylinder and being respectively provided with two folding blades and two folding jaws arranged 120° apart instead of 180° apart as is usual; the folding blade cylinder being also provided with two sets of grippers for receiving the collected groups of sheets from the collecting cylinder.

A practical embodiment of my invention is represented in the accompanying drawings, in which

Fig. 1 represents a diagrammatic view of the double folder showing both the right and left hand collecting, folding and delivery mechanisms.

Fig. 2 represents a detail vertical longitudinal section through the left hand collecting, folding and delivery mechanism.

Fig. 3 represents a similar section taken in another plane.

Fig. 4 represents a plan view of a portion of the left hand collecting, folding and delivery mechanism.

I will proceed to describe the left hand collecting, folding and delivery mechanism of the double folder, it being understood that the right hand mechanism is the same in reverse arrangement.

The pair of coacting two bladed rotary cutters for severing the superimposed webs into sheets of the desired length is denoted by 1 and 2. A pair of suitable guides 3 and

4 direct the sheets between the two bladed rotary tucker 5 and the collecting cylinder 6. This collecting cylinder 6 is provided with four sets of grippers 7. The folding cylinders are denoted by 8 and 9 and they are three-fourths the diameter of the collecting cylinder. The folding cylinder 8 is provided with two sets of grippers 10 arranged 120° apart for receiving the collected groups of sheets from the sets of grippers 7 on the four way collecting cylinder 6. This folding cylinder 8 is also provided with two floating folding blades 11 and 12 arranged to coact with the two sets of floating folding jaws 13 and 14 on the folding cylinder 70 9. The floating folding blades 11 and 12 are arranged 120° apart on their cylinder 8 and their corresponding floating folding jaws 13 and 14 are arranged 120° apart on their cylinder 9. The floating folding jaws 75 13 of the cylinder 9 are arranged to transfer their folded product to the set of grippers 15 carried by the lower delivery cylinder 16 and the set of floating folding jaws 14 of the cylinder 9 are arranged to transfer their folded product to the set of grippers 17 of the upper delivery cylinder 18. The sets of grippers 15 and 17 of these lower and upper delivery cylinders are arranged to deliver their folded products into their respective lower and upper left hand packer deliveries 19 and 20. Lower and upper slitters 21 and 22 may be provided for coaction with the lower and upper delivery cylinders to slit the collected and folded 90 product.

In the right hand collecting, folding and delivery mechanism the pair of coacting rotary cutters are denoted by 23, 24, the rotary tucker by 25, the collecting cylinder 95 by 26, the folding cylinders by 27, 28, lower and upper delivery cylinders by 29, 30 and the lower and upper right hand packer deliveries by 31, 32. The gears connecting the right and left hand mechanisms are denoted by 33, 34, which gears may be disconnected where it is desired to use only one of the mechanisms. The gear which connects the collecting cylinder 6 with the rotary cutter 1 is denoted by 35 and the gear which connects the collecting cylinder 26 with the rotary cutter 24 is denoted by 36.

The usual cams are provided for operating the grippers, blades and jaws at the proper times for producing the desired re- 110

sults, which cams will not be specifically described herein as they are so well known in this art.

An example of the various deliveries is as follows: In handling the product of a double web press in which each press carries seventy-two plates and each plate cylinder carries thirty-six plates, six around and six across, the wide webs are slit into two narrow ribbons of equal width. When running three 48s and three 32s and three 16s combinations, the four narrow webs are superimposed and carried to the left hand mechanism. On the remaining products one-half of the product of the press is carried to each of the mechanisms. In this case only two narrow webs are superimposed.

Therefore, when only one of the collecting, folding and delivery mechanisms is used, the 48 page product is delivered to the upper packer delivery. When 16 and 32 page combinations are delivered in a single collecting, folding and delivery mechanism the 32 page signatures are delivered to the upper packer delivery and the 16 page signatures to the lower packer delivery. When the right and left collecting, folding and delivery mechanisms are used, the 24 page products are delivered to the upper packer delivery of the right hand mechanism and to the upper packer delivery of the left hand mechanism. The 16 and 8 page combinations are run double, i. e. the 16s to the upper packer delivery of each mechanism and the 8s to the lower packer delivery of each mechanism.

From the above description it will be seen that by making the collecting cylinder of each mechanism a four-way cylinder and by making the folding cylinders three-fourths the diameter of the collecting cylinder and by arranging the folding blades and folding jaws 120° apart instead of 180° apart as they would be for a press having a cylinder with either four or eight plates around its circumference, I am enabled to collect, fold and deliver 8s and multiples of 8s from a rotary printing press having six plates around printing cylinders.

By the term "cylinder" as used in the description, I contemplate any equivalent means for passing the sheets and signatures through the prescribed paths, and by the term "grippers" I wish to include any equivalent devices suitable for the purpose of leading the sheets or signatures through said prescribed paths.

What I claim is:—

1. A mechanism arranged to collect, fold and deliver signatures of 8s and multiples of 8s, comprising a four-way collecting cylinder and two coacting folding cylinders, the first folding cylinder being arranged to take the sheets from the collecting cylinder and fold them off to the second folding cylinder.

2. A mechanism arranged to collect, fold and deliver signatures of 8s and multiples of 8s to two delivery points, comprising a four-way collecting cylinder, two coacting folding cylinders and two delivery cylinders, the first folding cylinder being arranged to take the sheets from the collecting cylinder and fold them off to the second folding cylinder and the second folding cylinder being arranged to transfer the so folded sheets to the two delivery cylinders. 75

3. A mechanism arranged to collect, fold and deliver various signatures, comprising a four-way collecting cylinder having four sets of grippers 90° apart and two folding cylinders three-fourths the diameter of the collecting cylinder, one folding cylinder having two sets of grippers 120° apart and two folding blades 120° apart and the other folding cylinder having two sets of folding jaws 85 120° apart.

4. A mechanism arranged to collect, fold and deliver various signatures to two delivery points, comprising a collecting cylinder having four sets of grippers 90° apart, two folding cylinders three-fourths the diameter of the collecting cylinder, one folding cylinder having two sets of grippers 120° apart and two folding blades 120° apart and the other folding cylinder having 95 two sets of folding jaws 120° apart and two delivery cylinders having sets of grippers coacting with their respective sets of folding jaws.

5. A mechanism arranged to collect, fold and deliver signatures of 8s and multiples of 8s, comprising a collecting cylinder having two sets of grippers 90° apart and two folding cylinders three-fourths the diameter of the collecting cylinder, one folding cylinder having two sets of grippers 120° apart and two folding blades 120° apart and the other folding cylinder having two sets of folding jaws 100 120° apart. 105

6. A mechanism arranged to collect, fold and deliver signatures of 8s and multiples of 8s to two delivery points, comprising a collecting cylinder having four sets of grippers 90° apart, two folding cylinders three-fourths the diameter of the collecting cylinder, one folding cylinder having two sets of grippers 120° apart and two folding blades 120° apart and the other folding cylinder having two sets of folding jaws 110 120° apart and two delivery cylinders having sets of grippers coacting with their respective sets of folding jaws. 115

7. In a double folder, two mechanisms arranged to collect, fold and deliver 8s and multiples of 8s, each mechanism comprising a four-way collecting cylinder and two coacting folding cylinders, the first folding cylinder being arranged to take the sheets from the collecting cylinder and fold them off to the second folding cylinder. 125 120

8. In a double folder, two mechanisms arranged to collect, fold and deliver signatures of 8s and multiples of 8s to two delivery points, each mechanism comprising a four-way collecting cylinder, two coating folding cylinders and two delivery cylinders, the first folding cylinder being arranged to take the sheets from the collecting cylinder and fold them off to the second folding cylinder and the second folding cylinder being arranged to transfer the so folded sheets to the two delivery cylinders.

9. In a double folder, two collecting, folding and delivery mechanisms, either arranged to collect, fold and deliver 48s or 32s and 16s and each arranged to collect, fold and deliver 24s or 16s and 8s, each mechanism comprising a four-way collecting cylinder and two coating folding cylinders, the first folding cylinder being arranged to take the sheets from the collecting cylinder and fold them off to the second folding cylinder.

10. In a double folder, two collecting, folding and delivery mechanisms, each having upper and lower deliveries, either mechanism being arranged to collect, fold and deliver 48s to the upper delivery or 32s to the upper delivery and 16s to the lower delivery, and each mechanism being arranged to collect, fold and deliver 24s to the upper delivery or 16s to the upper delivery and 8s to the lower delivery, each mechanism comprising a four-way collecting cylinder, two coating folding cylinders and two delivery cylinders, the first folding cylinder being arranged to take the sheets from the collecting cylinder and fold them off to the second folding cylinder and the second folding cylinder being arranged to transfer the so folded sheets to the two delivery cylinders.

In testimony, that I claim the foregoing as my invention, I have signed my name this fifth day of May A. D. 1927.

HOWARD M. BARBER.
